UNITED STATES PATENT OFFICE.

GEORGE L. SCALES, OF DETROIT, MICHIGAN.

PAPER-MATERIAL CONTAINER.

1,231,203.

Specification of Letters Patent. Patented June 26, 1917.

Application filed December 30, 1915. Serial No. 69,502.

To all whom it may concern:

Be it known that I, GEORGE L. SCALES, a citizen of the United States of America, residing at Detroit, in the county of Wayne and State of Michigan, have invented certain new and useful Improvements in Paper-Material Containers, of which the following is a specification, reference being had therein to the accompanying drawings.

- 10 This invention relates to a paper-material container, and besides possessing rigidity and durability as prerequisite of this character of container, it possesses all of the characteristics essential for a perfect sanitary receptacle. The most important sanitary characteristic is that of a protected and clean pouring edge and this feature is embodied in my invention by a novel form of closure, which fits over the pouring edges of 15 the container and maintains the same in a sanitary condition from the producer of the contents of the container to the consumer of the contents, irrespective of the nature of the liquid container.
- 20 25 From a manufacturing standpoint, the container possesses those characteristics which lend ease to manufacture of the container, facilitate filling and closing the container, and permit of the container being 30 readily opened.

The above and other advantages will appear as the nature of my invention is better understood, and reference will now be had to the drawing, wherein

35 Figure 1 is a vertical sectional view of a paper-material container embodying characteristics of my invention;

Fig. 2 is a cross sectional view of a closure for the container, and

40 Fig. 3 is a side elevation of a portion of the container.

In the drawings, 1 denotes a paper-material body of any cross sectional area, said body having an end thereof permanently closed, as at 2. The opposite end of the body provides a pouring edge 3, and my invention particularly relates to the closing of the open end of the body and the protection of the pouring edge 3 thereof.

45 50 Fitted over the pouring edge 3 of the body 1 is a closure made of a paper-material and this closure has an annular outer depending flange 5 and an annular inner flange 6 of less depth than the annular flange 5, said flanges being disposed to coöperate with the closure in forming an annular

groove 7 to receive the pouring edge 3 of the body 1. The closure 4 has a central annular depressed portion 8 provided with a concentric opening 9 having for its walls an inwardly projecting flange or seat 10 adapted to receive an ordinary paper-material cap or seal, such as commonly used for closing milk bottles.

The outer depending flange 5 of the closure 4 has diametrically opposed depending gummed tabs or tongues 12 adapted to be secured to the walls of the body 1 to hold the closure upon said body.

In the construction of the body 1 and the closure 4 a very durable paper-material is used which can be rendered impervious and non-absorptive by paraffin, gelatin, or a similar material, applied in a thin coat by dipping or otherwise. The closure 4 may 70 be made of one or more plies of paper-material pressed or otherwise shaped as above defined, and as illustrated, the closure is made of two plies with the innermost ply forming a stiffening or reinforcing member 75 for the outer ply. The innermost ply includes the annular depending flange 6, also another depending flange 13 which adds rigidity to the depressed portion 8 of the closure. These two plies when glued or 80 otherwise connected together and incased in paraffin present practically a homogeneous mass and the closure can be easily mounted upon the pouring edge of the body 1 and secured thereto by the tabs or tongues 12. 90 Paraffin may be also used to seal the closure 4 relative to the body 1 and to remove the closure, it is only necessary to cut the tabs or tongues 12 and give the closure 4 a slight 95 twist to release the same relative to the body 1.

The opening 9 permits of the container being filled and the producer of the contents of the container can easily place the cap 11 in position to close the container. The cap 100 is sprung into the depressed portion of the closure and frictionally held therein. In some instances it may be hermetically sealed upon the flange or seat 10 by paraffin, and instead of removing the cap 11 to obtain the 105 contents of the container, the closure 4 is bodily removed, thus providing a clean and sanitary pouring edge for the contents of the container.

By reference to Fig. 1, it will be observed 110 that the closure is comparatively flat and as a modification of this construction, there is

shown in Fig. 2 a closure similar in construction but substantially frusto-conical shape in elevation, such closure tending to shed liquid or any matter that may lodge 5 thereon contiguous to the side walls of the container.

What I claim is:—

A closure for a paper-material container, comprising paper-material formed with 10 outer and inner annular depending flanges providing a groove adapted to engage over the edge of a container with the outer flange of greater depth than the inner flange, said closure having a central depressed portion

providing an opening concentric with the 15 container and a seat at the marginal edges of said opening to receive a flat cap adapted to be sprung into the opening of the closure on to the seat to lie in a plane well below the top of the closure, and tabs secured to the 20 outer flange of said closure and adapted for attachment to the walls of the container.

In testimony whereof I affix my signature in presence of two witnesses.

GEORGE L. SCALES.
